UNITED STATES PATENT OFFICE.

MELVILLE CLARK, OF CHICAGO, ILLINOIS, ASSIGNOR TO MELVILLE CLARK PIANO COMPANY, OF CHICAGO, ILLINOIS, A CORPORATION OF ILLINOIS.

PIANO-PLAYER EXHAUST AND REGULATING MECHANISM.

1,184,723.

Specification of Letters Patent.

Patented May 30, 1916.

Application filed March 5, 1915. Serial No. 12,319.

To all whom it may concern:

Be it known that I, MELVILLE CLARK, a citizen of the United States, residing at Chicago, in the county of Cook and State 5 of Illinois, have invented new and useful Improvements in Piano-Player Exhaust and Regulating Mechanism, of which the following is a specification, reference being had to the accompanying drawings, forming a 10 part thereof.

The purpose of this invention is to provide an improved construction of exhaust and controlling mechanism for a pneumatically-operated player piano, and particularly it is designed to afford such improved mechanism in a form adapted to be mounted 15 in a player's bench.

It consists in the elements and features of construction shown and described as indicated in the claims.

In the drawings: Figure 1 is a vertical section of a player's bench containing the mechanism constituting this invention shown in elevation partly sectional looking 25 toward the piano. Fig. 2 is a similar view showing said mechanism as it is seen looking away from the piano. Fig. 3 is a vertical section at the line, 3—3, on Fig. 1. Fig. 4 is a detail horizontal section at the line, 30 4—4, on Fig. 3. Fig. 5 is a detail horizontal section at the line, 5—5, on Fig. 1. Fig. 6 is a vertical longitudinal section of a portion 35 of a piano case, showing the exhaust mechanism and supporting and operating parts in front elevation, mounted in the piano casing, substantially in the same manner as they are shown in Fig. 1 and Fig. 2, mounted in the bench. Fig. 7 is a detail 40 transverse section of an air trunk connection. Fig. 8 is an axial section of the same. Fig. 9 is a section at line 9—9 on Fig. 2. Fig. 10 is a diagrammatic view of the electric switch box.

The pumping mechanism, or the exhaust mechanism, herein shown and to be described, is in its general structure adapted to be mounted in any sort of casing, and can be mounted in the lower part of a piano casing if so desired, and it is so shown in 45 Fig. 6; but it is particularly designed and adapted for mounting in a casing of suitable proportions to adapt it to constitute a player's bench, or in a casing mounted on and comprising a part of a player's bench; 50 and it will first be described in connection

with the player's bench which is shown in the drawings as a rectangular casing comprising end walls, 1, 1, a bottom, 2, a front wall, 3, and rear wall, preferably made as swinging doors, 4, 4, and the top or seat board, 5. The exhaust mechanism shown is designed to be operated by an electric motor shown at 6, mounted upon the bottom. Preferably, in order to deaden the sound, the mount, or support for this motor, comprises 65 a base member, 7, having end and middle ribs, 8, 8 and 9, across which there is stretched a piece of leather belting, 10, upon which the motor is supported by springs, 11, coiled around bolts, 12, which take 70 through the foot lugs, 6^a, and extend through the springs and through the leather belt, and through wooden cross bars, 6^b, below the belt and are provided below said cross bars with nuts, 6^c, by which a limited degree 75 of tension is put upon the springs in securing the motor to the belt, which is further elastically supported by springs, 6^d, under the cross bars. This method of supporting the motor for deadening the sound is not a 80 part of the present invention, being substantially covered by my Patent No. 1,013,862, granted January 9, 1912.

The drawings show speed-reducing connections from the motor for rotating a 85 crank-shaft, 15, journaled in hangers, 16, 16, and having a single crank, 17, connected by pitmen, 18 and 19, respectively, with the moving members, 20 and 21, of two similar double-acting pumper bellows, each comprising two fixed walls, 22, 23, between which the moving walls, 20 and 21, of the bellows, respectively, vibrate, being connected therewith by the bellows sides, 24, 24, for inclosing the bellows chambers. Said fixed 90 walls have air outlet ports, 23^a, controlled by valve, 22^a, seating against the entrance of air. The chambers on opposite sides of the respective moving or vibrating members, 20, 21, of these pumper bellows communicate 95 with a common exhaust chamber, 25, at what may be called the heel of the bellows, through ports which are controlled by valves, 26, 26, opening to permit the air to pass from said exhaust chamber into the 100 pumper chambers, respectively, and seating in the opposite direction to prevent the air passing back into the exhaust chamber. The two exhaust chambers, 25, 25, are connected by an air trunk, 28. These two 105 110

similar double-acting pumper devices are mounted respectively upon two walls of the casing which are at right angles to each other, and, as shown, upon one end wall and the top wall, the crank-shaft, 15, being parallel to said walls and to the angle between them in said angle, and thereby being adapted to operate both the pumper bellows and give them alternate movement,—that is, to cause the same phases of their movement to alternate,—by means of a single crank, as shown and described.

From the exhaust chamber of that bellows which is mounted upon the end wall 15 of the casing, and which has its heel at the lower end corner of the casing, an air trunk connection, 30, is provided which leads through the casing and is adapted for exterior attachment thereto of a flexible air trunk, 29, which may lead to the pneumatic action in the piano which is to be served by this exhaust mechanism when the latter is mounted as shown and described in the player's bench or other casing detached from the piano casing.

The exhaust chamber of one of the pumpers, most conveniently the one which is mounted under the top wall of the casing or seat of the bench, 25, leads by an air trunk, 35, to a relief box, 36, (through which the air enters freely past sound muffling devices, not shown), the communication of the air trunk with the relief box being controlled by a valve, not shown, which is operated by a mechanism, B, the character of which is fully shown and described by United States Patent No. 1,136,656, dated April 20, 1915, and which need not be described here further than to point out that it comprises two motor pneumatics, B¹, B², which by connections (not shown in the drawings) rotate a gear wheel, B³, which engages a rack, B⁴, and that this rack, B³, is extended and connected to a lever, 25^b, fulcrumed at 25^a on the casing, and connected with the stem, 26, of the valve, (not shown) which controls communication of the air trunk, 35, with the relief box and muffler, 36. This mechanism, B, is controlled in its operation by air ducts, 31, 31, which lead to nipples, 32 and 33, which are mounted in the air trunk connection, 30, above mentioned leading from the exhaust chamber, 25, of the vertically-positioned pumper out through the casing for connection by a proper air trunk with the piano. These nipples, 32 and 33, having their inner ends open within the air trunk connection, 30, are adapted to be connected by air tubes similar to the tubes, 31, which may extend in an air trunk to be provided leading from the bench to the piano casing, and to be connected with a similar fitting that is, a fitting similar to the connection, 30, having the nipples, 31, 31,—mounted on

the piano casing, from the inner end of which nipples proper air tube connections will extend to the tracker ducts or manually-controlled devices for controlling atmospheric communication of said ducts, and thereby operating the primary pneumatics which form part of the mechanism, B, to cause the motor pneumatics, B¹, to operate the mechanism for moving the rock, B. These connections mounted on the piano casing are not shown, being identical in construction with the fitting, 30, having the nipples, 32, 33, mounted on the piano bench casing, as described.

The electric circuit wires for energizing the motor are shown at 40, 40, leading from a switch device, 41, mounted on the bench casing and most conveniently positioned at the upper forward left-hand corner, said fitting extending to the outer surface of the 85 casing for receiving the usual plug connection with an exteriorly-located source of electric energy. This switch device comprises a lever, 42, fulcrumed on a bracket, 43, mounted on the right hand end of the 90 bench casing, said lever having two push rods, 44 and 44^a, connected to it at opposite sides of the fulcrum, each extending out through the end of the bench casing, so as to be accessible for pushing in one or the other to shift the switch in one direction or the other. It is designed and necessary that the switch device should be operated manually for throwing on the current to start the motor, but it is adapted to be operated either manually or automatically for opening the switch and shutting off current. The manual operation for that purpose has already been indicated. For automatic operation to open the switch, there is provided a motor pneumatic, 45, mounted upon the right hand end wall of the bench casing, having connected with it a lever extension arm, 46, which projects in proximity to the rearwardly extended end of the lever, 42, 110 in position to encounter and actuate that lever upon collapse of the pneumatic, and by that movement to move the lever in direction for opening the switch. The motor pneumatic, 45, is controlled by a primary 115 pneumatic, 48, which is contained within an exhaust box, 49, connected by a tube, 50, with the exhaust chamber, 25, of the horizontally-positioned pumper, and by an air tube, 51, with said motor pneumatic, 45. Said primary pneumatic, 48, is controlled by a duct, 52, leading from said primary pneumatic to a nipple, 53, mounted similarly to the nipples, 32 and 33, in the connection, 30, and having its inner end open within 125 said connection, adapted to receive a flexible tube to extend out through the air trunk to be provided leading across from the player's bench to the piano and in the piano casing connected to the inner end of a simi 30

lar nipple in a similar fitting, as above described mounted on the piano casing and having its inner end leading to the tracker duct which is to be provided for automatically controlling the switch to cut off the current upon the conclusion of the playing.

The speed-reducing connections between the motor and the crank-shaft comprise the counter shaft, 60, journaled in a rocking frame or bracket, 61, fulcrumed at 62, near the bottom of the casing, and having an arm, 63, whose slotted end receives a threaded post, 64, on which are adjusting nuts, 65 and 66, above and below said engaged ends of the arm, 63, by which said frame, 61, is adjusted by rocking it over its fulcrum, 62, to carry the shaft, 60, toward and from the motor shaft. On the shaft, 60, there is a large pulley, 65, connected by a belt, 66, with the pulley, 67, of the motor, and a smaller pulley, 68, connected by a belt, 69, with a pulley, 70, on the crank shaft. It will be noticed that the relative positions of the three shafts, the motor shaft, the shaft, 60, and the crank shaft, 15, are such that the rocking of the frame, 61, to carry the shaft, 60, operates simultaneously to tighten or slacken both the belt, 66 and 69. In a mechanism for such a purpose, and particularly in devising such mechanism for having it contained in the very limited space conveniently available for it, either in the piano casing or in the player's bench casing, as shown, especially in view of the fact that such a mechanism must be attended to by persons who are not expert mechanics, it is of great importance that the expedient for keeping the parts properly adjusted to insure continuous and uniform transmission of the power of the motor to the crank shaft should be simple and accessible, and such as to require the minimum exercise of mechanical judgment in operating them; and such a device is that shown for adjusting the belts.

I claim:—

1. In combination with a player's bench forming a casing, an exhaust device mounted within the casing, an exhaust-tension-controlling device also mounted within the casing; air tube connections for operating the tension-controlling device; an air trunk connection from the exhaust device adapted for attachment of a flexible tube to lead away from the bench, said trunk connection having means leading into it for attaching the air tube connections from the tension-controlling device, and for connecting also air tubes leading out of said exhaust trunk connection and away from the bench; whereby the exhaust pipe which leads away from the bench may contain the air tubes for operating the exhaust tension controlling device.
2. In combination with a player's bench forming a casing; an exhaust device

mounted within the casing; an electric motor also mounted within the casing for operating the exhaust device, an electric switch for controlling the motor; a pneumatic device for operating the switch; two separate tubes leading to the outside of the bench casing, one being an air tube for controlling said pneumatic device and the other being an exhaust trunk connection from the exhaust device leading to the outside of the bench casing.

3. In combination with a player's bench forming a casing, an exhaust device mounted within the casing; a motor also mounted within the casing for operating the exhaust device; an electric switch for controlling the motor; a pneumatic device for operating the switch; an air tube for controlling said pneumatic device; a connection from the exhaust device extending out through the wall of the casing, adapted at the outer end for connecting a flexible pipe to form an exhaust trunk leading away from the casing, and connected at the inner side of the casing wall with the exhaust device, said connection having means for connecting the air tube from said pneumatic device inside the casing wall, and also for connecting an air tube to lead away from said connection outside the casing wall.

4. In combination with a player's bench forming a casing, and, mounted in and supported upon such casing, a rotary motor; a crank shaft driven by the motor; two pumbers having their exhaust members communicating each operated by the crank shaft, a relief device communicating with the pumbers; air tubes for controlling the operation of the relief device; an air trunk connection leading from a pumber exhaust chamber; and adapted for attachment of a flexible tube to lead away from the bench, nipples leading into said air-trunk connections and interiorly and exteriorly open for attachment of air tubes thereto, said air tubes being connected with the outer ends of said nipples.

5. In combination with a player's bench forming a casing and mounted in such casing, an electric motor, a crank shaft operated by the motor, two pumbers having their exhaust chambers communicating, operating connections to both said pumbers from the crank shaft, an electric switch for controlling the motor, a motor pneumatic for operating said switch, an exhaust box having air connections with a pumber exhaust chamber, a primary pneumatic contained in said exhaust box, a duct connecting the exhaust box with the motor pneumatic, a valve controlling said duct operated by the primary pneumatic, an air tube leading to said primary pneumatic, an air trunk connection from the pumber exhaust chamber leading to the outside of the

bench casing, and an air tube connection from the primary pneumatic said air tube also leading to the outside of said casing.

6. In combination with a player's bench 5 constituting a casing, and contained within and mounted upon such casing, an electric motor, pumping mechanism operated by said motor, an air trunk connection for the exhaust chamber of the pumping mechanism extending out through the casing wall, an air trunk leading from said exhaust chamber to said connection within the casing, a switch for controlling the electric motor, a motor pneumatic for operating 10 said switch engaging therewith for opening the switch to disconnect the motor, manually operable means extending to the exterior of the casing for moving the switch, a box mounted in the casing having air 15 connection with the exhaust chamber of the pumpers and with said motor pneumatic, a valve which controls the last mentioned connection, a primary pneumatic in said exhaust box which controls said valve, an air 20 tube controlling said primary pneumatic, a 25

nipple mounted in said air trunk connection and exteriorly and interiorly open for connection of an air tube thereto, the exterior end of said nipple being connected with the air tube from the primary pneumatic.

30

7. In combination with a bench forming a casing; an exhaust device mounted within the casing; an electric motor also mounted in the casing for operating the exhaust device; an electric switch for controlling the 35 motor; a pneumatic device for operating the switch; two separate tubes leading to the outside of the bench casing, one being an air-inlet tube for controlling said pneumatic device, and the other being an exhaust 40 trunk connection from the exhaust device leading to the outside of the bench casing.

In testimony whereof, I have hereunto set my hand at Chicago, Illinois, this 1st day of March, 1915.

MELVILLE CLARK.
